DESIGN FOR AN OTTOMAN

Alphonse Brenner, Shreveport, La.

Application April 2, 1938, Serial No. 76,234

Term of patent 7 years

To all whom it may concern:

Be it known that I, Alphonse Brenner, a citizen of the United States and a resident of Shreveport, in the county of Caddo and State of Louisiana, have invented the new, original, and ornamental Design for an Ottoman, of which the following is a specification.

Reference is had to the accompanying drawing, forming part thereof.

I claim:

The ornamental design for an ottoman, as shown.

ALPHONSE BRENNER.
